UNITED STATES PATENT OFFICE.

SARAH E. CATTELL, OF MATTOON, ILLINOIS.

CLASP.

SPECIFICATION forming part of Letters Patent No. 375,475, dated December 27, 1887.

Application filed August 16, 1886. Serial No. 210,971. (No model.)

To all whom it may concern:

Be it known that I, SARAH E. CATTELL, of Mattoon, in the county of Coles and State of Illinois, have invented certain new and useful 5 Improvements in Clasps; and I do hereby declare that the following is a full, clear, and exact description thereof, reference being had to the accompanying drawings, and to the letters of reference marked thereon, which form a part 10 of this specification.

This invention relates to that class of clasps for detachably connecting straps or other articles to garments which comprise as their essential features a metal eye or loop attached 15 at one end to the strap or other article to which the clasp is permanently connected, and a movable headed stud or button adapted for engagement with the said loop or eye, and in which the aperture or opening of the latter is 20 provided with a narrow extension or slit adjacent to the free end of the loop, of suitable width to receive the shank of the stud, so that after one head of the stud has been inserted through the loop the stud-shank may be drawn 25 into the narrow part or slit of the loop-opening, so as to bind or hold the part of a fabric or garment placed over the head of the stud.

My improvement comprises a construction 30 of the loop whereby the latter is made flexible to enable it to tightly engage the stud, while at the same time allowing it to yield or expand and thereby adjust itself to thick or thin goods, and in which the slot of the loop is made narrower at its upper end to prevent the loop 35 from becoming too readily detached from the stud, as will hereinafter fully appear.

The invention consists in the matters hereinafter described, and pointed out in the appended claims.

40 In the accompanying drawings, illustrating my invention, Figure 1 is a perspective view of a preferred form of clasp embodying my invention. Fig. 2 is a perspective view of the same when engaged with the marginal part of 45 the garment. Fig. 3 is a side elevation of the clasp shown in Figs. 1 and 2. Fig. 4 is a side elevation, partially in section, of a clasp embodying my invention, illustrating another means of movably connecting the stud with 50 the loop.

As illustrated in the said drawings, A is the strap to which the clasp is attached.

B is a metal eye or loop connected at its upper end with the said strap, and C is the stud or button adapted for engagement with said 55 loop, said stud being provided with heads or flanges C' c and a shank, c'. The loop B is provided in its upper part, or that adjacent to its point of connection with the strap A, with an opening, b, of sufficient size for the convenient insertion of the head C' of the stud C, and at the lower part of said loop, or at its end remote from its point of attachment to the strap, is formed a narrow opening or slot, b', made of sufficient width to receive the shank 65 c' of the said stud, but narrower than the diameter of the head of said stud. Said loop B is made of flexible wire, as illustrated, or otherwise constructed in such manner that its sides are capable of bending or yielding outwardly, and the slot b' is made narrower at its upper than at its lower end, so that when the stud C is inserted in the said slot b' the sides of the latter will yield or spread to allow the passage of the stud downwardly into the lower 75 part of the slot, and will then close and act with a spring pressure to prevent the too easy disengagement of the stud from the loop.

The marginal part of a garment, as indicated, for instance, at D, Fig. 2, is connected 80 with the strap A by placing the said marginal part of the garment over the head C' of the stud C, then inserting the said head through the aperture b of the loop B, and then drawing the stud downwardly into the slot b' of the 85 loop, so as to draw and hold the fabric of the garment closely about the head of the stud, as clearly shown in Fig. 2. The elastic construction of the loop obviously allows the sides of the slot or slit b' to spring or yield outwardly 90 during the insertion of the stud, and to thereafter act with a constant pressure upon the material grasped between the loop and stud, so as to hold said material firmly and obviate liability of its slipping under a considerable 95 strain upon the parts.

It is entirely obvious that a clasp comprising the loop B and stud C will be of practical utility when the said stud is entirely disconnected from the other parts of the device. In 100 order, however, to insure the retention of the stud in proper position for use, I preferably connect said stud with the strap A and the upper end of the loop by means permitting

the necessary movement of the stud to enable it to be engaged with and disengaged from the loop in the manner above described. One desirable construction in a device for this purpose is shown in Figs. 1, 2, and 3, in which the said stud C is secured upon a flexible strap, E, attached to or forming a continuation of the strap A, the said strap E being of sufficient length to enable the stud to be drawn downwardly into the lower end of the slot b' of the loop. Another means for connecting the stud with the loop is shown in Fig. 4. In this instance, F is a metal plate provided with a longitudinal slot, f, in which the stud C is movably held by means of an extension, c', of the shank c, which extension c' passes through the slot f and a flange or disk, c³, secured to the shank-extension c' upon the side of the plate F opposite to that against which the flange c rests. In this example the loop B is connected with the upper end of the plate F by a hinged connection, b², and the strap A is connected with the said plate F by a loop upon the end of the strap, engaged with an opening or eye, f', at the upper end of the plate, as shown.

In the operation of engaging with the edge of a garment a clasp of this form the lower end of the loop B is swung away from the plate F, the stud C thrust upwardly in the slot f until opposite the opening b of the loop and the marginal part of the garment placed between the loop and the plate over the head of the stud, the loop is swung toward the plate so as to carry the head through the opening b, and the stud then drawn or slid downwardly in the slot until it engages the lower end of the slot, so as to hold the garment therein in the manner before described.

Although the form of the device shown in Fig. 4 is one of practical utility, I prefer that illustrated in Figs. 1, 2, and 3 as affording the same result with a cheaper and more simple construction of the parts. In the particular construction of the parts illustrated in said Figs. 1, 2, and 3 the wire loop B is connected with the strap A by means of a metal

plate, G, secured to the strap by an eyelet or rivet and bent into tubular form at its lower end to form an eye or a bearing, g, for the bent upper ends, b³, of the wire forming the loop, said wire being inserted through apertures b⁴ b⁴, formed in the eye g, so as to hold the loop from spreading at its upper part. This construction is novel, and inasmuch as it possesses particular advantage in connection with a wire loop, it is herein specifically claimed. In the particular construction of the parts shown in said figures, furthermore, the strap E is made continuous with the strap A by doubling the said strap A upon itself and securing the hinged plate G to the said strap at the upper end of the double part.

I claim as my invention—

1. The combination, in a clasp, of a headed stud, a spring-metal loop having the upper end of its opening enlarged to receive the head of the stud, the lower end of said opening of less breadth than the head of the stud and the intermediate portion of said opening normally narrower than the shank of the stud, and means, substantially as described, for connecting the parts, as set forth.

2. A clasp comprising a flexible wire loop or eye having a narrow slot at its lower end and provided with outwardly-bent parts b³ b³ at its upper end, a stud provided with two disks or flanges adapted for engagement with the said loop, a flexible strap connecting said stud with the loop, and a metal plate, G, attached to the strap and provided with a bearing, g, for the parts b³ b³ of the loop, said bearing g being provided with apertures b⁴ b⁴, through which the end parts of the wire composing the loop are inserted, substantially as described.

In testimony that I claim the foregoing as my invention I affix my signature in presence of two witnesses.

SARAH E. CATTELL.
